UNITED STATES PATENT OFFICE.

ARTHUR B. KENDRICK, OF EAST ORANGE, NEW JERSEY, ASSIGNOR TO JAMES R. KENDRICK CO., INC., OF PHILADELPHIA, PENNSYLVANIA, A CORPORATION OF PENNSYLVANIA.

ABDOMINAL BELT OR SUPPORTER.

1,063,922.

Specification of Letters Patent.

Patented June 3, 1913.

Application filed April 29, 1911. Serial No. 624,214.

To all whom it may concern:

Be it known that I, ARTHUR B. KENDRICK, a citizen of the United States, residing at East Orange, in the county of Essex and 5 State of New Jersey, have invented certain new and useful Improvements in Abdominal Belts or Supporters, of which the following is a specification.

This invention relates to abdominal belts 10 or supporters of that class which include a body belt portion and thigh straps attached to the sides of the belt portion.

The object of the invention is to provide a belt or supporter of novel, simple and efficient construction, having provision whereby the body belt portion and the thigh straps may each be rendered longitudinally elastic and the elastic portions of the straps so related to the elastic portions of the body belt 20 that the entire device may readily adapt itself to the figure of the wearer in a manner to permit the device to be worn with ease and comfort while performing its function as a supporter.

With the object thus generally stated, the invention will be hereinafter more fully described and particularly pointed out in the claim.

In the drawings: Figure 1 is a face view 30 of my improved abdominal belt or supporter, in flattened out condition. Fig. 2 is a front view thereof, as applied to the body of a person. Fig. 3 is an enlarged detail showing the adjacent elastic threads of the 35 body belt portion and one of the thigh straps and the knitted binder threads in which the elastic threads are woven and which attach the thigh straps to the body belt.

1 designates the body belt portion constructed of longitudinally-extending elastic threads 2 interwoven with or bound together by knitted binder threads 3, as shown in Fig. 3. The binder threads 2 are not shown in Figs. 1 and 2, because the scale is too 40 small, but it will be readily understood that the elastic threads 2 are bound together throughout the entire body belt portion by a continuous net work of the knitted binder threads shown in Fig. 3, thereby rendering 45 said portion longitudinally elastic. The central portion of the body belt is fashioned wider than the end portions thereof by shirring, as shown. Sewed or otherwise secured to each end of the body belt 1 is a 50 piece of leather 4 or other suitable material

provided with eyelets 5 to receive a suitable lacing to draw the ends of the body belt toward each other and secure them together after the belt has been placed around the body of the wearer with the widened central 60 portion in the abdominal region. To protect the wearer from the lacing engaged with the eyelets 5 I provide one end of the body belt 1 with a flap 6 adapted to lie between the lacing and the wearer when the 65 belt is in use. The body belt 1 is provided with suitably located stays 7, as shown. Attached to the body belt 1 are thigh straps 8 each of which is constructed of longitudinally-extending elastic threads 9 interwoven 70 with or bound together by knitted binder threads 14, as shown in Fig. 3. The binder threads 14 are not shown in Figs. 1 and 2, on account of the small scale, but it will be understood that the elastic threads 9 are 75 bound together throughout by a continuous network of the knitted binder threads shown in Fig. 3, thereby rendering said straps longitudinally elastic. Sewed or otherwise secured to one end of each strap 8 is a piece 80 of leather 10 or other suitable material provided with a longitudinally-arranged series of eyelets 11; and sewed or otherwise secured to the other end of each strap 8 is a piece of leather 12 or other suitable material 85 provided with a hook 13.

After the body belt 1 is applied to the wearer the straps 8 are passed around the thighs of the wearer and after being adjusted to the desired degree of tightness one 90 of the eyelets 11 of each strap is engaged with the hook 13 of each strap thereby securing the ends of each strap together. Each thigh strap is attached to the body belt 1 between the points 14 and 15 one strap 95 on one side and the other strap on the other side of the body belt. The elastic threads 9 of each strap 8 between the points 14 and 15 extend substantially parallel to the adjacent elastic threads 2 of the body belt 1 between 100 the points 14 and 15; and each strap 8 is attached to the body belt 1 by having the knitted binder threads 10 interlaced with the knitted binder threads 3 between the points 14 and 15 as shown in detail in Fig. 3. 105 It will thus be seen that on each side of the entire device the body belt 1 and the thigh strap 8 form in effect an unbroken piece of fabric of substantially parallel elastic threads interwoven with a continuous net- 110

work of knitted binder threads extending from the top of the body belt 1 to the bottom of the thigh strap 8 between the points 14 and 15.

5 By the construction of the thigh straps, and by the arrangement of the threads of the thigh straps relatively to the threads of the body belt 1 hereinbefore described I have discovered that the thigh straps 8 will 10 hold the body belt down in position and at the same time give ease and comfort to the wearer. During various body movements of the wearer, each side of the entire device between the points 14 and 15 will yield not 15 only in a longitudinal direction but also in a diagonal direction.

In the drawings I have shown each thigh strap 8 formed of two sections of interwoven elastic threads and binder threads, the two 20 sections of each strap being joined by having a piece of tape 16 sewed to the meeting ends thereof.

I claim:

An abdominal belt or supporter compris-

ing a body belt portion provided with longitudinally-extending elastic threads interwoven with binder threads rendering said portion longitudinally elastic, said portion being Shirred and having the lower elastic threads of its sides converging downwardly 25 at an angle with relation to its upper threads, means for securing the ends of said portion together, thigh straps attached to the bottoms of the sides of said portion and being provided with longitudinally-extending elastic threads interwoven with binder threads and rendering said straps longitudinally elastic, the elastic threads of each strap extending substantially parallel to the adjacent elastic threads of said portion, and 30 means for securing the ends of said straps together.

In testimony whereof I affix my signature in presence of two witnesses.

ARTHUR B. KENDRICK.
